(57) **CLAIM**

The ornamental design for a walker adapter, as shown and described.

DESCRIPTION

FIG. 1 is a top perspective view of the walker adapter.

FIG. 2 is a front perspective view of the walker adapter.

FIG. 3 is a top view of the walker adapter.

FIG. 4 is a bottom view of the walker adapter.

FIG. 5 is a right side view of the walker adapter.

FIG. 6 is a left side view of the walker adapter.

FIG. 7 is a front view of the walker adapter; and,

FIG. 8 is a rear view of the walker adapter.

The broken lines in FIG. 2 define the bounds of the claimed design and form no part thereof.
